STRIPPER MECHANISM FOR ENCAPSULATING MACHINES

Rex E. Moule, Holden, Mass., assignor to Norton Company, Worcester, Mass., a corporation of Massachusetts

Application March 2, 1951, Serial No. 213,626

20 Claims. (Cl. 18—1)

1

The invention relates to a stripper mechanism for encapsulating machines.

One object of the invention is to provide a reliable stripper mechanism to remove capsules from the network of gelatin from which they were formed. Another object of the invention is to provide a compact mechanism of the type indicated. Another object of the invention is to provide a stripper mechanism which tends to urge the network in a forward rather than a retrograde direction whereby to avoid moving the network in a retrograde direction. Another object of the invention is the provision of a stripper mechanism which gently vibrates the network, which has a salutary effect on the encapsulating operation as will be hereinafter explained. Another object of the invention is to provide a stripper mechanism having some of the advantages otherwise pointed out and adapted to segregate the capsule into two approximately equal proportions so that the receiving trays, not shown, one on either side of the network will be filled at approximately equal rates. Another object of the invention is to provide a stripper mechanism of the characteristics indicated which can readily be opened up for threading the machine. Another object of the invention is to provide a stripper mechanism which will successfully operate with gelatin sheets and network of different thickness. Another object of the invention is to provide a stripper mechanism which will readily strip capsules of different sizes and shapes and having different orientations. In this connection some capsules are spheres and others are prolate spheroids and in the latter case the major axis may be disposed at various angles relative to the network.

Other objects will be in part obvious or in part pointed out hereinafter.

In the accompanying drawings illustrating one of many possible embodiments of the mechanical features of this invention;

Figure 1 is a plan view of the stripper mechanism,

Figures 2 and 3 are cross-sectional views taken respectively on the line 2—2 and the line 3—3 of Figure 1,

Figure 4 is a front elevation of the mechanism,

Figure 5 is a side elevation of the mechanism,

Figure 6 is a fragmentary rear elevation showing a part of the driving mechanism,

Figure 7 is a fragmentary vertical sectional view taken on the line 7—7 of Figure 1.

Referring first to Figure 5, the encapsulating machine has a vertical wall 10 which serves as a support for much of the encapsulating mechanism. Referring now to Figure 1, the encapsulating mechanism and the stripper mecha-

2

nism, the latter being more particularly the subject matter of the present invention, are mounted in a frame having a back wall 11 and a front wall 12, only portions of which are illustrated herein. The encapsulating mechanism which actually forms the capsules 15 from the sheets 16 of gelatin or the like is supported, guided and journaled in this frame which includes the walls 11 and 12. I shall not herein describe the encapsulating mechanism in detail since the capsules may be formed by any mechanism desired and this present invention deals with mechanism to strip the capsules from the network 17 of gelatin and its relation to take-up means to keep the network taut. However, the encapsulating mechanism including the apparatus for forming the sheets or ribbons 16, for bringing them together, for forming capsules 15 while filling them with some material such as 10 medicament, for example vitamins, may be as disclosed in my copending application Serial No. 48,912, filed September 11, 1948, now Patent No. 2,549,327, granted April 17, 1951. With regard to terminology, the material is referred to as sheets or ribbons before it is brought together, then it is, by the mechanism of the above application, formed into tubes one-half of each tube being derived from one sheet or ribbon and the other half being derived from the other sheet or ribbon, and finally from these tubes the capsules are died out, whereupon the remainder of what originally was the sheets is referred to as network. This invention, therefore, deals with the material after it has become capsules and network.

It will be seen from Figure 5 that the capsules 15 extend in horizontal as well as in vertical lines, that is to say after capsule formation the network 17 holds capsules 15 extending for a limited distance vertically and also from edge to edge of the network in a series of parallel horizontal rows which also forms a series of parallel vertical rows. The purpose of the mechanism of this invention is to strip these capsules from the network and discharge them into trays, not shown. It is also pointed out that while the die mechanism which forms the capsules cuts the gelatinous tubes annularly and severs some of the capsules formed out of the tubes from the network, others of the capsules are still held to the network by filaments or thin membranes of gelatin, quite tenuous indeed and capable of being broken by mechanical action but nevertheless strong enough to hold the capsules to the network in the absence of mechanical means to force them therefrom.

Referring now to Figures 1, 5, 6 and 7, secured to the vertical wall 10 is a bracket 19 support-

ing an electric motor 20 having a shaft 21 upon which is secured a sprocket pinion 22 which drives, by means of a sprocket chain 23, a sprocket gear 24 secured to a shaft 25 that extends through a plate 26 and the walls 10 and 11 and is journalled therein. Referring now especially to Figure 7, a pinion gear 28 is secured to the shaft 25 at the end thereof opposite the end to which the sprocket gear 24 is secured. This pinion gear 28 meshes with a small gear 29 which is mounted in a housing 30 (see also Figure 4) secured to the back wall 11. This small gear 29 and a larger gear 31 are secured directly to it are keyed or otherwise removably secured to a shaft 32 which is journalled in the housing 30, the housing 30 having an irregularly shaped opening 33 to accommodate the gears 28, 29 and 31. The housing 30 can be secured to the wall 11 in any suitable manner, such as by means of screws 34 (see Figures 1 and 7).

The gear 31 meshes with a gear 35 which, as will be seen from Figure 7, is a little bit larger than the gear 31, but this relationship might readily be reversed and furthermore the gears 31 and 35 might be the same size although it is preferred to have them slightly different in size. The gear 35 is secured to a shaft 36 which is suitably journalled in a manner which will presently be explained. Before doing so the strippers 40 and 41 mounted on and secured to the shafts 32 and 36 respectively will be described and explained.

These strippers 40 and 41 are illustrated in Figures 1, 3, 4 and 5 and preferably are paddles, using that word in the sense in which it was used to describe the propelling device of a river boat having a stern paddle. They are preferably made of rubber and by that I mean rubber which is flexible and easily bent. Such rubber can be made out of the material caoutchouc by mixing it with only a minor proportion of sulphur, and vulcanizing. The paddles 40 and 41 are vulcanized to the shafts 32 and 36 respectively so they have to revolve when the shafts are revolved. In this embodiment of the invention each one is shown as having four blades 42 although a lesser or greater number could be provided. As a further description of the flexibility of the paddles two blades which normally are at an angle of 90° to each other can readily be brought into contiguous and parallel relation by the fingers alone without the use of any tool and neither are they injured by this test. Naturally some filler is compounded with the caoutchouc; the usual filler carbon black being quite satisfactory, and other ingredients will naturally be added such as an accelerator and possibly some zinc oxide, this being a matter for rubber chemists and being known to those skilled in that art. Clearly other materials such as the so-called synthetic rubbers can be substituted for natural rubber, for example butadiene-styrene, butadiene-acrylic nitrile and chloroprene can be used. I shall term these materials collectively "flexible elastomer" and naturally this comprises other flexible rubbery-like materials. While I have given a good example of how flexible is this rubber which I have actually used, it should be understood that somewhat stiffer rubber can also be used with good results. However some degree of flexibility is highly desirable and is preferred and I believe it is better to have the rubber about as flexible as indicated.

Referring now to Figures 1 and 2, secured to the inside of the front wall 12 as by means of

5 a locating pin 45 and a screw 46 is a plate 47 having a bearing 48 journalling the front end of the shaft 32. The shaft 32 and therefore the paddle stripper 40 are thus mounted for rotation on a fixed axis.

Referring now to Figure 5, extending between and journalled in the walls 11 and 12 is a rock shaft 50. Referring now to Figures 3 and 5, an irregularly shaped lever 51 has at one of its three ends a slot 52 through which extends a clamping screw 53; the slot 52 merges with a hole through which the rock shaft 50 extends. By tightening the screw 53 the irregular lever 51 can be clamped to the rock shaft 50. A second end of the lever 51 has a hole 54 by means of which it is connected to a spring 55 the other end of which is connected to a stud 56 projecting from the wall 11. Near the third end of the lever 51 the shaft 36 is journalled in the lever. A screw 58 extends through this end of the lever 51 and abuts the housing 30; by means of the screw 58 the stripper 41 can be adjusted in position relative to the stripper 40 within the limits of relative movement of the gears 31 and 35 without causing them to bind or unmash. It will be seen that the spring 55 urges the lever 51 in a counter-clockwise direction, Figure 3, to hold the screw 58 against the housing 30 but permitting the lever to be moved in a clockwise direction by superior force.

Referring now to Figure 2, the other end of the shaft 36 is journalled in a bearing 59 provided in one of the three ends of an irregularly shaped lever 61 having a slot 62 and a clamping screw 63 by means of which it can be secured to the rock shaft 50. This lever 61 which is of substantially the same shape as the lever 51, by means of a pin 64 is connected to a spring 65 the other end of which is connected to a stud 66 projecting from the inside of the wall 12. As in the case of the lever 51, the end of the lever 61 in which the shaft 36 is journalled has a screw 68 extending through it which abuts the plate 47, and by adjusting the screw 68 the front end of the stripper 41 can be adjusted relative to the stripper 40. Of course the screws 58 and 68 should both be turned whenever it is desired to adjust the stripper 41 since it is desirable that the axes of the shafts 32 and 36 be maintained parallel to each other. It will now be seen that if either one of the levers 51 or 61 be moved against its spring 55 or 65, the rock shaft 50 will be turned and so therefore the other of these levers 51 and 61 will be moved against its spring and this action withdraws the paddle 41 from the paddle 40 momentarily unmashing the gear 35 from the gear 31 and this is done for the purpose of threading the machine, whereupon these parts may be allowed to move back again to the position illustrated in the drawings.

60 For that purpose I provide, as shown in Figures 1, 2, 4 and 5, a knob 70 on the front end of a shaft 71 which is journalled in and extends through the wall 12 and secured to which at the other end thereof is an eccentric disc 72 having a pin 73 normally engaging a stationary pin 74 projecting from the inside of the wall 12. When the knob 70 is turned to move the pin 73 away from the pin 74, the eccentric disc 72 engages 65 the pin 64 and thus moves the lever 61 against its spring 65 and this action moves the stripper 41 away from the stripper 40 so that the machine can be readily threaded. Figure 5 probably best illustrates the parts just described and their relative positions.

Referring now to Figures 5 and 6, a chain 80 is continuously moved by a source of power and through reduction gearing which is not illustrated herein, since it is part of the main driving mechanism of the encapsulating machine and that is described in my patent above referred to. The chain 80 drives a sprocket gear 81 which is secured to a shaft 82 that extends from the vertical wall 10 through a bracket 83 and is journaled in the wall and in the bracket, the latter being secured in any suitable manner to the wall 10. Secured to the protruding end of the shaft 82 is a disc 84 having a slideway 85 in which are a fixed block 86 and a movable block 87. A screw 88 extends through and is journaled in the block 86 but can not move longitudinally relative thereto on account of an integral collar 89 and a bolt head 90 secured to the screw 88. The other end of the screw 88 extends into a threaded hole in the movable block 87, and it will now be seen that the block 87 can be adjusted in the slideway 85 by turning the bolt head 20.

Secured to and projecting from the block 87 is a stud 95. A long link 96 extends from the stud 95 to a pin 97 extending through and between the forked ends 98 of a forked block 99 which is keyed to a shaft 100 on the outer end of which is secured a collar 101. It will therefore be seen that continuous rotation of the disc 84 causes oscillations of the shaft 100, and the amplitude of these oscillations can be varied from zero up to a considerable number of degrees by adjustment of the block 87.

Still referring to Figures 5 and 6, the shaft 103 is journaled in the walls 10 and 11 and also in a bracket 104 secured to the bracket 83 and another collar 105 on the shaft 100 adjacent the bracket 104 prevents any longitudinal movement of the shaft to the right, Figure 5. Secured to the shaft 100 adjacent the wall 10 is a gear 106 which meshes with a gear 107 secured to the outer element of an overrunning clutch 108. The inner element of the overrunning clutch 108 is secured to a shaft 111. I have not illustrated the mechanism of this overrunning clutch 108 since these are now standard articles readily procurable and widely understood. This particular clutch 108 is set to revolve the shaft 111 intermittently in a counter-clockwise direction, Figure 4, responsive to oscillations of the gear 107 which is oscillated by the gear 106 on the oscillating shaft 100. These overrunning clutches function like a ratchet wheel and a set of pawls on a coaxial wheel, either of which may be driven thus to drive the one intermittently in a given direction when the other one is oscillated, but there is little or no lost motion or backlash in these overrunning clutches.

Near its rear end the shaft 111 extends through and is journaled in the walls 10 and 11. At its front end the shaft 111 is connected to the inner element of another over-running clutch 114 the outer element of which is located in and supported by the wall 12 and a front plate 115, being secured to the wall 12. This over-running clutch 114 prevents retrograde movement of the mechanism responsive to the reaction of the network 17. Keyed to the front of the shaft 111 and desirably removable therefrom is a crank 117 whereby the shaft 111 may be turned in a forward direction as the over-running clutches do not prevent this but they do prevent turning in a retrograde direction.

Referring now to Figures 2, 3 and 5, a fluted

steel roll 120 is secured to the shaft 111. This is one of the take-up rolls. As shown in Figure 2, a gear 121 secured to the shaft 111 meshes with a gear 112 which is secured to a fluted steel roll 123 which is the other of the take-up rolls. These rolls 120 and 123 grip the network 17 and move it downwardly intermittently. They grip it taut and enable the encapsulating mechanism to die out good capsules from the network. The roll 123 is rotatably mounted on a shaft 124 which as indicated in Figure 3 has an eccentric circular end piece 125 journaled in a hole in the wall 11. A similar circular eccentric circular end piece 126 is shown in Figure 4 and this is journaled in the front plate 115. A pin 127 extends laterally from the end of the piece 126 which projects beyond the front of the plate 115. Connected to the end piece 126 is a circular plate 128 having a slot therein through which extends a screw 130 projecting from the plate 115. By moving the pin 127 clockwise, the roll 123 can be moved away from the roll 120 thus separating them for the purpose of threading the machine. The gears 121 and 122 will readily mesh and unmash. The screw 130 acts as a stop. A large screw 131 extending through the plate 115 from the bottom thereof and into the hole therein which journals the eccentric circular end piece 126 can be used to lock the shaft 124 in operative take-up position or in open position as desired.

Secured to and extending between the irregularly shaped levers 51 and 61 is a sheet metal deflector 135 which extends the length of the stripper 41 and beyond. On the other side of the network 17 secured to and extending between the housing 30 and the plate 47 is another deflector 136 and this extends the length of the stripper 40 and beyond. As well shown in Figure 3, these deflectors guide the capsules 15 over the take-up rolls 120 and 123 thus preventing them from being entrapped and smashed by these rolls.

I have found that not only are the strippers herein described very effective for removing capsules but also that they vibrate the network 17 which has the effect of driving out air bubbles from the medicament before the capsules are sealed by the dies (not shown). They also appear to eliminate sticking of the network and/or the capsules to the dies and arbors (not shown). The strippers rotate in a forward direction, that is to strip the capsules downwardly and of course the rolls 120 and 123 move intermittently in a downward direction so therefore there is no tendency of the strippers to pull the network back if for any reason the grip of the rolls is weak. Thereby the strippers have no detrimental action upon the encapsulating operation proper and in fact they have beneficial effects thereon. It is found in practice that about half of the capsules end up on one side of the network and half on the other. While by reason of the difference in sizes of the gears 31 and 35, the stripper 40 rotates a little faster than the stripper 41, strippers rotating at the same rate would also be effective. By rotating them at different rates, however, the blades 42 on one side are not always opposite the blades 42 on the other side and this varying of phase relationship causes the blades to hit some capsules in one direction and other capsules in the other direction and it is believed to be beneficial, at least it has been found to work well in actual practice. Consequently I prefer the arrangement shown and described. There is nothing wrong with Figure 3 in showing a capsule 15 on either side of the network since

inspection of Figure 5 shows that there is more than one capsule to be removed at each level.

Each of the strippers 40 and 41 rotates so fast that the peripheries of the paddles 42 move faster than the network 17 when the network is moving. Thus at all times when capsules 15 come within reach of the blades they are brushed downwardly and out of the network. The action, however, is not positive insomuch as the blades 42 will bend and for this reason as well as on account of the out of phase relationship described, the breaking of a capsule into two halves is a rare occurrence. It will be seen moreover that the strippers in combination with the deflectors achieve a sort of pinching action to squeeze the capsules 15 out of the network 17 and this action is aided by the downward movement of the network past the deflectors and again the out of phase relationship of the strippers causes this pinching action to occur usually at one side or at the other of the network 17 rather than simultaneously on both sides thereof. However certain advantages of the invention would be achieved even if the strippers rotated in a retrograde direction to force the capsules up in which case the deflectors would not be needed.

It will thus be seen that there has been provided by this invention apparatus in which the various objects hereinbefore set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. Apparatus of the class described comprising a pair of capsule strippers in the form of paddles having long blades, said blades being connected together, bearings for said paddles mounting them close together and substantially parallel to each other, take-up means to move a network of gelatin in a given direction, said paddles being located one on either side of said network, and mechanism to rotate said paddles so that the blades when they are adjacent the network move in the same direction as the network is moved, said paddles being made of flexible material.

2. Apparatus as claimed in claim 1 in which the flexible material is flexible elastomer.

3. Apparatus as claimed in claim 2 having a pair of deflectors extending across the network and between the strippers and the take-up means, said deflectors extending close enough to the network to prevent capsules from entering the take-up means.

4. Apparatus as claimed in claim 3 having movable mountings for the bearings for one of the paddles and for one of the deflectors, whereby a paddle and a deflector can be moved away from the other paddle and deflector for the purpose of threading the machine.

5. Apparatus as claimed in claim 4 in which the mechanism to rotate the paddles is geared to move one of the paddles at a greater speed than the other thereof.

6. Apparatus as claimed in claim 1 having a pair of deflectors extending across the network and between the strippers and the take-up means, said deflectors extending close enough to the network to prevent capsules from entering the take-up means.

7. Apparatus as claimed in claim 6 having mov-

able mountings for the bearings for one of the paddles and for one of the deflectors, whereby a paddle and a deflector can be moved away from the other paddle and deflector for the purpose of threading the machine.

8. Apparatus as claimed in claim 7 in which the mechanism to rotate the paddles is geared to move one of the paddles at a greater speed than the other thereof.

9. Apparatus as claimed in claim 1 having movable mountings for the bearings for one of the paddles, whereby a paddle can be moved away from the other paddle for the purpose of threading the machine.

10. Apparatus as claimed in claim 9 in which the mechanism to rotate the paddles is geared to move one of the paddles at a greater speed than the other thereof.

11. Apparatus as claimed in claim 1 in which the mechanism to rotate the paddles is geared to move one of the paddles at a greater speed than the other thereof.

12. Apparatus of the class described comprising a pair of parallel take-up rolls mounted for rotation with their surfaces spaced a small distance apart such as to receive and take-up a network of gelatin in which capsules have been formed, driving mechanism simultaneously but intermittently to rotate said rolls in the same take-up direction, i. e. with adjacent surfaces moving in the same direction, a pair of parallel paddles having flexible blades mounted for rotation on axes parallel to the axes of the take-up rolls and mechanism for rotating said paddles in directions of rotation with adjacent peripheries moving in the same direction which is the same direction as that in which the adjacent surfaces of the rolls move.

13. Apparatus as claimed in claim 12 in which the mechanism for rotating the paddles rotates them at different speeds.

14. Apparatus as claimed in claim 13 having a pair of capsule deflectors one being between one take-up roll and the adjacent paddle, and the other deflector being between the other take-up roll and the other paddle.

15. Apparatus as claimed in claim 14 in which the flexible blades are made of flexible elastomer.

16. Apparatus as claimed in claim 12 having a pair of capsule deflectors one being between one take-up roll and the adjacent paddle, and the other deflector being between the other take-up roll and the other paddle.

17. Apparatus as claimed in claim 16 in which the flexible blades are made of flexible elastomer.

18. Apparatus as claimed in claim 12 in which the flexible blades are made of flexible elastomer.

19. Apparatus of the class described comprising a pair of capsule strippers in the form of paddles having long blades, said blades being connected together, bearings for said paddles mounting them close together and substantially parallel to each other, take-up means to move a network of gelatin in a given direction, said paddles being located one on either side of said network, and mechanism to rotate said paddles, said paddles being made of flexible material.

20. Apparatus as claimed in claim 19 in which the mechanism to rotate the paddles is geared to move one of the paddles at a greater speed than the other thereof.

REX E. MOULE.
